PAPER CLIP

Application filed October 28, 1929. Serial No. 402,978.

The invention relates to paper clips and a primary object of the invention is to so construct a clip of this character that it may be easily adjusted for use in clamping together a few sheets or a large number equally well without crimping or buckling of the paper.

Another object of the invention is to so construct a clip of this character that it may be formed from a single piece of wire and bent to shape and hence cheaply manufacture.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 is a perspective view of a thick package of paper or cards with this improved clip shown applied;

Fig. 2 is a similar view with the clip shown applied to a small package;

Fig. 3 is a perspective view of the clip detached, and

Fig. 4 is a view similar to Fig. 3 with the clip in reversed position.

In the embodiment illustrated the paper clip comprising this invention is made from a piece of wire of any desired or suitable size according to the size of the clip and the use to which it is to be put. This clip which is numbered 1 is formed from a piece of wire by bending it first into rectangular shape to provide a square loop 2 and the remainder of the wire is then bent to V-shaped form as shown at 3 and the apex 4 of this V-shaped loop is made of a length to overlie the lower cross bar 5 of the square loop. Both ends of the wire are left free and extend in the same direction, one being located at one corner of the clip and the other at the opposite corner thereof.

In the application of the clip the U-shaped portion numbered 6 is applied to one face of the package of paper or cards to be clipped as shown in Fig. 1 and the V-shaped loop 3 is placed on the opposite face of the package with the connecting bar or rod 7 thereof arranged diagonally across the end of the package. When so positioned it will be seen that the two members of the clip will lie flatly

against the opposed faces of the package and thus securely hold the sheets or cards together without buckling or crimping of the paper.

Owing to the connection of the two clamping members 3 and 6 by the rod 7 which connects said clamping members at their opposite upper corners, this rod forms a diagonal connector when applied and permits these two members to be positioned flat against the faces of the sheets clamped.

It is of course understood that these clips may be made of any gauge wire desired and the clips may be of any size.

When the clip is placed over a thick package of paper, no matter how strong the spring wire may be the V-shaped portion will be sprung at the lower cross arm about one-eighth of an inch and by reversing the V-shape member to the opposite side of the lower cross arm, the members will firmly grip a thin package. This constitutes an essential feature of the invention.

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed.

I claim:

A paper clip composed of a piece of wire bent to form a U-shaped and a V-shaped clamping member arranged in overlapping relation with a rod connecting the upper corner of one member with the upper corner of the other member, the free ends of said wire being oppositely positioned at the corners of the clip, and the apex of the V-shaped member lying against one face of the lower cross bar of the other member and shiftable to position said apex against the other face of said lower cross bar to adapt the members of the clip to effectively clamp the paper when in either position.

HENRY J. RIES.
